UNITED STATES PATENT OFFICE.

ARTHUR F. POOLE, OF PELHAM MANOR, NEW YORK, ASSIGNOR TO REMINGTON ACCOUNTING MACHINE CORPORATION, OF NEW YORK, N. Y., A CORPORATION OF NEW YORK.

CALCULATING MACHINE.

Application filed July 6, 1922. Serial No. 573,111.

To all whom it may concern:

Be it known that I, ARTHUR F. POOLE, citizen of the United States, and resident of Pelham Manor, in the county of Westchester and State of New York, have invented certain new and useful Improvements in Calculating Machines, of which the following is a specification.

This invention relates to calculating machines and especially to combined typewriting and calculating machines which contain clearance proof mechanism.

The principal object of the invention is to improve clearance proof mechanism that is described and claimed in my application filed April 19, 1921 and bearing Serial No. 462,628. The invention set forth in that application includes, among other things, means for printing and registering numbers according to a special program, and clearance proof mechanism that is brought into action automatically at a predetermined point in said program.

To those skilled in the art, and aided by Patent No. 1,270,471 granted June 25, 1918, to assignee of J. C. Wahl, full knowledge of this invention will be imparted by the following description and accompanying drawings, although the drawings show only a small part of the machine which that patent describes.

In these drawings,

Figure 1 is a diagrammatic front elevation of mechanism comprised in a Remington accounting machine that embodies the invention;

Figure 2, a right side and sectional elevation of a fragment of the machine;

Figure 3, a sectional plan of another fragment;

Figure 4, a skeletonized perspective of mechanism partly illustrated in Fig. 1;

Figure 5, a front elevation of some of the mechanism shown in Fig. 1 but on a larger scale than Fig. 1;

Figure 6, a perspective of devices shown in the upper part of Fig. 5; and

Figure 7, an enlarged sectional plan of one of those devices.

Similar reference numerals designate like parts in different views.

The drawings represent the invention in a form in which it is embodied in combined typewriting and calculating machines, such

as are known as Remington-Wahl cross foot-

ing or Remington accounting machines. The construction and operation of such machines, not including clearance proof mechanism, is explained in the above mentioned Patent 1,270,471, to which reference is made for a description of any mechanism which these drawings do not show and which Remington-Wahl machines include, or any mechanism which is particularly referred to and not fully illustrated herein. It will be understood that the invention claimed herein may be adapted and applied to different forms of calculating machines.

The platen 1, type bars 2, and keys 3, conventionally shown in Fig. 1, are well known parts of the Remington typewriting machine, which the Remington-Wahl machine includes. The numeral keys are connected with the actuator of the calculating mechanism by links 4 and other links in rear of links 4 connect the keys with the type bars of the typewriter. The bar 5 is part of the stationary framework of the Wahl mechanism, this bar being a casting which is fast on the framework of the typewriter. The plates 6 and 7 and the block 8 (Figs. 1 and 2) are parts of the framework of the cross-footing mechanism. Plate 6 is attached by screws at its upper end to the right end of bar 5, plate 7 is attached to plate 6 and to another part of the framework, and block 8, which is a casting, fits between and is fastened to plates 6 and 7. The screw 9 (Fig. 2) is one of the fastenings. It passes through an ear on block 8 and thence into plate 7.

A typical instance of a set-up of the Remington accounting machine includes two vertical totalizers 10 and 11, and two dummies 12 and 13, mounted on the decimal carriage or truck, which is supported by rolls at the middle of the machine and connected with and partly supported at its ends by the typewriter carriage, and which travels towards the left and towards the right with the typewriter carriage. These dummies do not contain computing mechanism, each consisting merely of the framework of a totalizer, but they perform important functions which affect the actions of the cross totalizer. These functions would also be performed by complete totalizers which might be substituted for the dummies.

Each of these totalizers and dummies is secured on the truck by means which is well

known, and which is described in said Wahl patent. Each of the totalizers is of the ordinary Wahl construction, and is adapted to be actuated by the main master wheel of 5 the machine when motion is imparted to this master wheel from the numeral keys 3 and through the links 4 and other devices, as explained in the Wahl patent. The decimal scale 14 on each totalizer or dummy and the 10 pointer 15 (Figs. 1 and 3) coact in the operation of the machine in a well known manner. This pointer is attached to the bracket 16, which is fast on bar 5 about midway between its ends.

15 The truck 17 is the cross-footing carriage which is mounted on block 8 and travels on the ball bearings 18, and to which is connected the long tension coil spring 19 that runs over a pulley and draws the carriage 20 towards the right when it is allowed to move in that direction.

25 The totalizer 20 (Figs. 1, 2 and 5) is the cross-footing jumping totalizer mounted on truck 17 and arranged to be operated by the 30 cross-footing actuator comprising the master wheel 21 (Fig. 2).

35 In the operation of the machine, the truck 17, which normally stands at the right end of its path of travel, is picked up at times 40 by the vertical totalizers and dummies by means of the hook 22, pivoted at 23 on bracket 24 fast on the truck 17. This hook engages a lug, such as lug 25 (Fig. 4), formed on the right side plate of each vertical totalizer and dummy. As a number is 45 written and calculated, truck 17 is drawn toward the left until the last carrying wheel 26 is engaged with master wheel 21, and at the next step of the carriage hook 22 is disconnected from the lug, whereupon the 50 cross-footing truck is drawn to the right by spring 19, the adjustable stop bar 27 on said truck striking lever 28 as the totalizer reaches normal position and forcing 55 the lever against frame plate 6. This lever is pivoted at 29 to an ear on plate 6, and spring 30 tends to swing the lever to the left. Slide link 31, through which lever 28 passes, 60 is movable by this lever a short distance to the left or right in guides formed in the framework. When this link or slide is moved it rocks bell crank 32, pivoted at 33 to the framework and supporting at its left end the blocking device 34 pivoted to the 65 bell crank at 35 and hanging close to the front end of fixed stud 36 having the longitudinal slot 37 in its under side. The construction is such that when lever 28 is in the position shown in Fig. 1, to which position it is turned by spring 30, the lower end of blocking plate 34 is above slot 37, and when the lever is in contact with plate 6, the lower end of plate 34 is about even with the under side of stud 36. The swinging or angular movement of plate 34 on its

70 pivot 35 is controlled through pin 38 by link 39 pivoted at 40 to the depending arm of swinging frame 41, pivoted on rock shaft 42, which is journaled in the framework. The frame 41 has roller 43 on the arm 75 which extends to the left from shaft 42, which roller is normally held in an upper position by means of the spring 44 but is adapted to be depressed, when a vertical totalizer or dummy is over the master 80 wheel, by the track or rail 45 mounted in the casing of said totalizer or dummy (Fig. 4). Such a track or rail is more plainly shown in the side view of the cross totalizer (Fig. 2), which is like each of the vertical 85 totalizers plus clearance proof mechanism. The whole construction is such that when there is no vertical totalizer or dummy over the main master wheel then plate 34 has been swung so far to the left as not to be 90 able to cover slot 37 in post 36, but when a vertical totalizer or dummy passes over the master wheel then said plate is swung to the right far enough to enable it to cover the slot when the plate is in its lowest position. This is well known locking mechanism used in the Remington-Wahl machine and described in said Wahl patent. It will be perceived that it is so constructed that plate 34 cannot close the end of slot 37, except (1) when a vertical totalizer or dummy is over the main master wheel, and (2) when lever 28 is in its right-hand position, so that it requires a combination of two conditions to cause said plate to block up said slot. 95

100 Each of the links 4, when the key to which it is connected is struck, actuates or tends to actuate a device sometimes called a fan, which is adapted to engage the universal bar 46, consisting of a roller mounted in arms fast on the universal rock shaft 47, on which the arm 48 also is fast. The universal bar when it is moved by the fan is swung towards the front of the machine so that shaft 47 is rocked and a backward 105 angular movement is imparted to arm 48. This arm always moves into slot 37, except when, under the above mentioned combination of conditions, the slot is blocked by plate 34. Then shaft 47, universal bar 46, the fans, keys and other devices all are 110 locked, and the machine cannot be operated thereafter until plate 34 shall have been withdrawn from in front of slot 37. The described lock is a well known part of 115 the Remington-Wahl machine, and it is convenient to use it in connection with my improved clearance proof mechanism, but it is to be understood that other means for locking an essential part of the machine 120 might be substituted for it.

125 In the manufactured Remington-Wahl machine and that described in said patent, the rock shaft 42 has the arm 49 fast thereon and projecting leftward therefrom and 130

carrying the roller 50 adapted to co-operate with cam plates 51 mounted on the framework of certain of the vertical totalizers and dummies. This arm is urged upward to a limited extent by a spring not shown herein and when it is in its uppermost position the master wheel 21 of the cross footer is connected up for addition. When said arm occupies its lowest position said master wheel is connected up for subtraction, and when the arm occupies an intermediate position the master wheel 21 is not so connected to the rest of the actuating mechanism as to enable the cross footer to be operated. This arm therefore has a normal elevated position in which the cross footer is set for addition, a middle position in which said cross footer is disconnected, and a lowest position in which the cross footer is set for subtraction. The details of this automatic control of the state of the cross footing actuator are fully disclosed in the patent above referred to.

The machine can be set in various ways to perform over and over again a regular program of writing and calculation. Fig. 1 diagrammatically shows one instance of such a setting. The program here to be considered is that of making daily entries on ledger sheets which customarily consist of leaves in a loose-leaf book. According to this program the items written in one day are contained in four column positions: debtor, creditor, balance and old balance or pick-up-balance, said columns occurring on the paper in the order named and corresponding respectively to totalizers 10 and 11 and dummies 12 and 13. In using the machine when a ledger sheet is put into it around the platen 1, the first operation is to write the old or pick-up-balance in the fourth column. Usually this is written on the same line as the old balance which had been written in the third column at the next preceding operation on that particular ledger sheet. The operator, therefore, when the paper is put into the machine, turns the platen 1 to bring the last written line to the writing line and in column "4" copies the balance seen just to the left of it in column "3." The paper is then line-spaced and the carriage drawn back to begin a new line of writing. The debtor item is then written in column "1," and the creditor item in column "2," and the resulting balance is then written in column "3," and this is the end of the program. If there is more than one debtor or creditor item to be entered, the paper is line spaced and the second item written under the first, but in every case the writing of the new balance in column "3" is the last operation on that particular sheet at that particular time. This sheet is then removed from the machine, another sheet is inserted and the

program is repeated. In Fig. 1 the parts are shown in position for writing the digit of lowest order in the third column, and the next key-stroke, to write said digit, will end the program. This last key-stroke will cause the carriage to step one space to the left, and the cross-totalizer to be freed and allowed to snap back to its extreme right-hand position, or at least as far as "dummy" 13 will allow it to go. When the next ledger sheet is put into the machine the carriage is already in position to allow the operator to copy in the pick-up balance for that sheet.

In the program described the calculation of the new balance is effected on the cross totalizer 20, and this is accomplished by causing the pick-up-balance written in column "4" to be added into the cross totalizer, and the debtor item or items written in column "1" to be also added in the cross totalizer, and the creditor item or items written in column "2" to be subtracted in the cross-totalizer. At this time the cross-totalizer will show the new balance, and if the cross-totalizer is set for subtraction when the new balance is being copied in column "3," the copying of said new balance, if correctly done, will bring said cross-totalizer to zero. In this program, therefore, the cross-totalizer should always stand at zero when it is freed for its jump to the right by the next key-stroke made when the parts are in the positions shown in Fig. 1.

In order to cause the numbers to be automatically added and subtracted as described subtraction cam plates 51 are placed on totalizer 11 and "dummy" 12, but such a cam plate is not put on totalizer 10 or "dummy" 13. It will be observed that as far as carrying out this program is concerned totalizers 10 and 11 could also be "dummies" if preferred, but it is sometimes useful to preserve the grand total of all debtor items and of all creditor items and the first two columns have, therefore, been defined by totalizers rather than by "dummies." In some instances totalizers are used instead of the "dummies" 12 and 13, as the totals indicated at the end of the day can sometimes be used in checking up the work.

I have provided clearance proof mechanism with means for bringing it into operation automatically by the last key stroke in the program, this being the point in the program at which the cross totalizer should always be clear. In the present instance said clearance proof mechanism is brought into operation by the next step of the carriage from the position indicated in Fig. 1. At this same step the hook 22 will be released from the "dummy" 12 and the cross-totalizer will jump back to the right impelled by its spring 19.

A sheet metal plate 52 is secured on top

of the casting 5 by screws at 53, one of said screws being at the right and the other at the left of the bracket 16. Just at the right of said bracket 16 the plate 52 has bent upward therefrom a bracket comprising an upward part 54 and a forwardly extending horizontal part 55. A headed stud 56, riveted to the part 55 from the under side thereof, serves as a pivot for a bell crank having an upper leftward extending arm 57 and a lower rearward extending arm 58, the sheet metal of which the bell crank is constructed being bent as shown so as to pivot on the stud 56 at two points spaced apart. In order to accommodate the rearward arm 58 an opening 60 is cut in the bracket 54, one wall of said opening serving to limit the motion of the arm 58 toward the left. Said arm is drawn toward the left by means of a spring 61 connected to a fixed stud 62. A dog 63 is pivoted at 64 to the free end of the arm 57 and said dog has an arm 65 which is connected by means of a spring 66 with an ear 67 of the bell crank 57, 58, said spring tending to turn the forward projecting end of the dog toward the left. The motion of said dog in that direction relative to the arm 57 is limited by a pin 68 projecting from the dog in position to strike the arm 57. The forward end of said dog 63 is formed with a bevel 70 which, when the parts stand in the positions above described, as the last digit of the new balance is written, is engaged or about to be engaged by a trip 71 consisting of a cam made on the right-hand end of bar 72 secured to the top of the casing of "dummy" 12 by two screws of which one may be the pivot screw of the spring latch locking loop of the dummy. The construction is such that when the carriage takes its next step beyond the position indicated in Figs. 1 and 3, the bell crank 57, 58 will be rocked in a clockwise direction (Fig. 3) moving the arm 58 toward the right. During this same step of the carriage the cam 71 escapes from the dog 63 and allows said bell crank to be restored to its normal position by its spring 61, so that the motion of the arm 58 consists of a quick motion to the right and back again. After the cam 71 has escaped from the dog 63 and the carriage is drawn back toward the right to begin a new line, said cam, when it strikes said dog, does not rock the bell crank 57, 58 but only rocks the dog 63 about its pivot 64, and it is for this reason that the cam surface 70 is made on said pivoted dog instead of being formed on a rigid part of the bell crank.

Connected to the free end of the arm 58 of said bell crank is a push wire 73 which extends nearly to the right-hand side of the machine where its free end is guided in an opening in an ear 74 in a sheet metal bracket 75 bent up as shown in Figs. 1, 4, 5 and 6, and having in it two holes 76 (Figs. 6 and

4). The part of said bracket that contains said holes lies flat against the frame plate 6 and the screws that attach plate 6 to bar 5 pass through said holes and thus secure the bracket in place. When the wire 73 is pushed toward the right it operates the upward arm of a latch 77 pivoted to the bracket 75 on a headed stud 78.

All of the mechanism above described is also shown and described in my aforesaid application, Sr. No. 462,628. The herein described improvement made by me on the invention set forth in that application is contained in the novel bell crank presently to be described, and means which coacts therewith and is included with it in the clearance proof mechanism or combined clearance proof and locking mechanism.

The body of this bell crank, which is sometimes called the lock lever cam of the Remington accounting machine, is preferably a piece of sheet metal cut from a flat blank and bent as shown, but it might be a casting or forging. It has the arms 79, 80 and 81 and is pivotally attached to the ear 82 of bracket 75 by a stud 83 passing through a hub fast on the bell crank. Arm 80 includes the rearwardly extending part 84 in which is the open slot 85, and in this slot tongue 86 of bracket 75 fits loosely so that when the bell crank is rocked arm 80 is guided at its left end by this tongue. The rearwardly extending lug 87, on arm 81 at its upper end, projects over the horizontal arm of latch 77 on which arm of the latch near its right end is the shoulder 88, and when the latch and bell crank are in their normal positions, lug 87 is in contact with this shoulder and prevented by it from moving to the left. The spring 89 attached to arm 81 and to lug 90 on the latch tends both to pull the upper end of arm 81 to the left and to move the shoulder of the latch upward. Arm 79 has the off-set part 91 at its lower end and this part crosses and passes in front of lever 28 at its upper end, and has on it the rearwardly extending lug 92 and the finger piece 93. Lever 28 is kept by spring 30 in contact with lug 92 which crosses the left edge of the lever, except that the lever is forced from the lug by stop bar 27 whenever the cross truck returns to its normal position while latch 77 engages lug 87 of the bell crank.

To arm 80 is affixed the cam bar 94 which has at its left end the inclined edge 95. Between this bar and arm 80 are spacing blocks 96 into which pass the fastening screws 97 that also pass through arm 80, the blocks being reduced at their front ends and the reduced parts extending through the bar and being upset in depressions in its front face so that they do not project from that face. Obviously the bar and arm might be fastened together in some other way but the fastenings should not project from the front face 134

of the bar. The perforated ear 98 and the platform 99 (Figs. 5, 6 and 7) are formed on this bar by bent-over portions of the stock.

On the platform 99 is mounted the device which comprises the thin flat bar 100, and which is a guide that sometimes causes a finger carried by the totalizer 20 to act on cam bar 94 and sometimes is forced from its normal position and thus temporarily disabled. This bar lies on platform 99 and is pivoted to it at 101. That portion of the bar with which said finger makes contact is at the left end of bar 100 and consists of the downwardly and backward extending parts 102 and 103 of an arm bent from the stock that forms bar 100, the right end of part 102 being slightly wider than the left. Part 103, which is triangular or about so in shape, has the meeting edges 104 and 105 shown in Figs. 2 and 6 and indicated by dotted lines in Fig. 7. These edges meet, when the guide is in its normal position on cam bar 94, a little below and in front of the place on edge 95 of the cam bar where that edge is cut by the vertical plane that contains the line of intersection or common points of edges 104 and 105 (see Figs. 6, 7 and 2). The lug 106 (Figs. 1, 4, 5 and 7) formed on guide bar 100 extends downward between cam bar 94 and arm 80 of the bell crank and forms a stop that acts on bar 94 and arm 80 to limit angular movements of bar 100 on its pivot 101. When the guide is in its normal position on the cam bar, lug 106 is held in contact with arm 80 by spring 107 attached to lug 98 and to lug 108 formed on bar 100.

If wire 73 is pushed toward the right when latch 77 engages lug 87 of bell crank arm 81 as described, the shoulder of the latch is moved downward and out of engagement with that lug, and arm 81 moves to the left so that the bell crank takes the position shown in Fig. 5. The bell crank would so move, it will be seen, at the next step of the carriage from the position indicated in Fig. 1. Whenever the bell crank so moves, lever 28 is forced by lug 92 to the locking position of the lever, which then makes contact with plate 6 of the framework, but when the bell crank is in its normal position as shown in Fig. 1, lug 92 allows lever 28 also to assume its normal position. It will be understood, therefore, that when the bell crank is tripped or released from latch 77 by the stepping of the dummy 12 to its sub-units position, or that next below its units position, the described locking mechanism will be thrown in and will prevent further operation of the machine in calculating. In other words, it will prevent continuation or repetition of the program of operation of the machine.

Means are provided to immediately release the lock in case the cross totalizer 20 stands at zero. In the cross-totalizer (Fig. 2), each carrying wheel 26 meshes with an idler

pinion 109 which meshes with a pinion 110 on the side of the corresponding dial 111. Each of the pinions 110 has one short tooth 112 which, when the dial 111 stands at zero, occupies the position shown in Fig. 2. An arbor or rocking device 113 extends through the totalizer and at its ends has trunnions which are pivoted in the side plates of the totalizer. This rocking device is in the form of a comb, also called a feeler, comprising a series of feeler fingers 114. I have not illustrated this feeler comb in detail because it is a well known construction, an instance of it being shown for example in my patent No. 1,311,710 dated July 29, 1919. The construction is such that if all of the wheels of the totalizer stand at zero then the fingers 114 can occupy the forward position shown in Fig. 2, but if any one of said wheels does not stand at zero then said wheel will have a full length tooth thereon in front of a finger 114 and said rocking device will be forced to occupy a position in the rear of that shown in the drawing. A lever 115 is mounted on the rocking device 113 to which it is rigidly connected by a dowel pin 116, said lever being at the extreme right-hand side of the totalizer just inside the frame plate. At its rear end the lever 115 has a tooth 117 which enters a crotch in the forward end of an arm 118 of a bell crank which has an upwardly extending arm 119. This arm 119 projects above the casing of the totalizer, passing through a suitable slot in said casing, and has at its upper end the finger 120. The bell crank 118-119 is pivoted on a frame rod 121 constituting a well-known part of the Wahl totalizer.

The above mentioned application shows a tension spring that presses the feeler against the pinions, or against one or more of them, and an important object of this invention is to relieve the pinions of friction engendered by the action of such spring. In machines to which this invention is applied the feeler or comb, normally, either but lightly touches a pinion or pinions, or is out of contact with every one of them, so that little, if any, friction is caused by the action of the feeler on the pinions when any dial is turned.

Whenever the totalizer is clear, arm 119 may stand in or be moved to the position shown in Fig. 2, and when it is in that position a vertical plane passed through cam bar 94 from end to end and parallel to its faces cuts finger 120 lengthwise (see Fig. 7). If, however, the totalizer is not clear finger 120 is in front of that plane and cannot move back to it, for such movement would be prevented by the action on the feeler of the pinion or pinions of the uncleared dial or dials. The forward position of finger 120, or that in which it stands when the totalizer is not clear, is indicated by dotted lines in Figs. 2 and 7. Cam plate

- 94 is above the horizontal plane that contains the top of finger 120 when the lock lever cam or bell crank is in its normal position, but when that device is in the locking position shown in Fig. 5, then edge 95 of cam bar 94, or edge 104 of the guide pivotally mounted on that bar, is in the path of finger 120, as the jumping totalizer travels to the right from the place where it is released from a column totalizer or dummy. As dummy 12 steps to sub-units position at the end of a clearing operation, included in the above explained program, the lock lever cam is tripped and the cross totalizer snaps back as before explained. If the totalizer is clear and finger 120 is in the position indicated by dotted lines in Figs. 2 and 7, this finger strikes edge 104 of guide 100, 102, 103 and is guided backward thereby until it passes under edge 95 of the cam bar, and this it does a little before it reaches the place where edges 104 and 105 of the guide meet. Hence as finger 120 passes that place, the totalizer being clear, this finger is under edge 95 of the cam bar whether the finger was or was not in the position in which it is shown in full lines in Figs. 2 and 7 at the beginning of the jumping movement of the cross totalizer. Then this finger, acting on edge 95 of the cam bar, raises that bar and thus turns the lock lever cam until it is restored to its normal position and is there caught and held by latch 77. Consequently if the totalizer is clear, mechanism set, as the totalizer starts to jump, so that if the totalizer were not clear the machine would be locked, is released from the restraint during the jump of the totalizer. But if on the other hand, the totalizer is not clear, so that finger 120 cannot stand in or be guided to the position which would enable it to strike edge 95 of cam bar 94, then this finger strikes edge 104 of the guide and by its action thereon displaces the guide, forcing it to turn on its pivot 101 and allow the finger to pass between cam bar 94 and part 103 of the guide. In that case the lock lever cam is not restored to its normal position but continues so to act on lever 28 that the machine would be locked were a column totalizer or dummy, whether the cross totalizer was or was not coupled to it, to be brought over the main master wheel. Should the cross totalizer be picked up by a column totalizer or dummy and drawn by it to the left while the lock lever cam is in its locking position as shown in Fig. 5, finger 120 would act on edge 105 of guide 100, 102, 103 and, forcing the guide to yield, would pass between its guiding edges and cam bar 94, so that the lock lever cam would remain in that position ready to coact with a column totalizer or dummy in locking the

machine before any dial of the cross totalizer could be operated.

Immediately after guide 100, 102 and 103 is forced aside by finger 120 traveling in either direction, as described, spring 107 ⁷⁰ restores the guide to its normal position on the cam bar.

For reasons well understood by those skilled in the art, the wheels of the Wahl totalizer when brought to zero position are ⁷⁵ not always exactly aligned in that position, and it may therefore be necessary for the comb teeth 114 to exert an aligning action on said wheels by co-operation with the pinion teeth next adjacent the short teeth 112. Where, as in my prior application, Sr. No. 462,628, the feeler comb is constantly pressed against the pinions by a spring, it is necessary to make said spring strong enough to have the aligning action referred ⁸⁰ to. In the present invention the pressure is derived from the spring 107 and it is exerted only for an instant and only at the instant when it is needed and when the wheels are not being turned by the master wheel. It is therefore practicable to make said spring 107 stronger than would be desirable if it exerted its pressure on the comb at the time when the totalizer was being operated. Moreover, in the present invention, the comb and its connected parts are operated by a quick movement against the wheels, which has a better aligning action than the pressure of a continuously acting spring. My prior application filed April 15, 1921, Sr. No. 492,396, discloses a form of clearance proof mechanism in which the feeler comb is normally free of spring pressure and in which the pressure of a spring extraneous to the totalizer is brought to bear on said comb momentarily during and by reason of the jump back of the cross-truck, and said application contains claims to that construction broader than the claims in this present application. ¹⁰⁰

To aid in properly locating guiding tongue 86 of bracket 75, so as to force cam bar 94 always to travel in its true path, as well as to prevent it from springing when finger 120 acts on the guide as described, bracket 75 may be provided with the forwardly extending part 122 which is held tight against the back of fixed bar 5 to which the bracket is attached. ¹¹⁰

It will be perceived that at a definite point ¹¹⁵ in the program the lock is always made effective and that it is kept so if the cross-totalizer is not clear, but immediately is automatically disabled if that totalizer is clear. The construction is such that if the operator fails to copy the total correctly the machine will be locked up against a continuation or repetition of the program, but if the total is copied correctly then there will be no interruption at all in the operation of ¹²⁰ ¹²⁵ ¹³⁰

the machine, which may go on exactly as if the clearance proof mechanism were not present. In case of an error, the operator, finding the machine locked may restore the lock lever cam to its normal position by pushing on finger piece 93, thus unlocking the machine, and then proceed to correct the error in the usual way.

Although in the machine of the above mentioned application Sr. No. 462,628 the pressure exerted by the comb on the pinions of the dials is too slight to impair very greatly the action of the machine, still it is desirable entirely to eliminate such pressure, so as not to subject the small and light mechanism of a totalizer to the extra work and stress imposed on it by such pressure. Therefore this improvement, by means of which that result is effected, is of considerable importance. Machines to which it is applied are more durable and more nearly perfect in action than are similar machines containing clearance proof mechanism which comprises a feeler or comb that is made to coat with register wheels by a spring constantly forcing it against them.

Various changes may be made in the details of construction and arrangement without departing from my invention.

Since mechanism such as that above described and called clearance proof mechanism actually tests and indicates the state or condition of the calculating machine as well when clearance is not proved as when it is proved, that mechanism properly may be called condition testing and indicating mechanism and be understood to include forms of condition testing mechanism differing from that shown herein in respect both to the details of their construction and their relations to those parts of the machines which are directly affected by their testing action and which may differ in different machines.

What I claim as new and desire to secure by Letters Patent, is:—

1. In a calculating machine, the combination with a group of register wheels, a carriage, and a feeler arranged to act on the group of wheels, of feeler-actuating means composed of two parts, one mounted on the carriage and transportable thereby to and from the other which is mounted on the framework, and one including an angularly movable device that has a finger and the other including a guide that acts on the finger at one side thereof.

2. In a calculating machine, the combination with a group of register wheels, a carriage, and a feeler arranged to act on the group of wheels, of feeler-actuating means composed of two parts, one mounted on the carriage and including an angularly movable device that has a finger, and the other mounted on the framework and including a

guide that acts on the finger at one side thereof.

3. In a calculating machine, the combination with a traveling totalizer, and a feeler arranged to act on register wheels in the totalizer, of feeler-actuating means composed of two parts, one mounted in the totalizer and having a finger projecting from the top thereof, and the other mounted on the framework and including a guide that acts on the finger. 70 75

4. In a calculating machine, the combination with a traveling totalizer, and a feeler arranged to act on register wheels in the totalizer, of feeler-actuating means composed of two parts, one mounted on the totalizer and transportable thereby to and from the other, which is mounted on the framework, and one including an angularly movable device that has a finger, and the other including a guide that acts on the finger at one side thereof. 80 85

5. In a calculating machine, the combination with a traveling totalizer, and a feeler arranged to act on register wheels in the totalizer, of feeler-actuating means composed of two parts, one mounted on the totalizer and including an angularly movable device that has a finger, and the other mounted on the framework and including a guide that acts on the finger at one side thereof. 90 95

6. In a calculating machine, the combination with a group of register wheels, a carriage, and a feeler arranged to act on the group of wheels, of feeler-actuating means in which a part mounted on the carriage and a part mounted on the framework are included, and locking mechanism including a movable device arranged to be actuated by that part of said means which is mounted on the carriage during a transit wherein said means has previously actuated the feeler. 100 105

7. In a calculating machine, the combination with a traveling totalizer, and a feeler arranged to act on register wheels in the totalizer, of feeler-actuating means in which a part mounted on the totalizer and a part mounted on the framework are included, and locking mechanism including a movable device arranged to be actuated by that part of said means which is mounted on the totalizer during a transit wherein said means has previously actuated the feeler. 110 115 120

8. In a calculating and recording machine, the combination with a jumping totalizer, and a feeler contained in and arranged to act on register wheels of the totalizer, of feeler-actuating means composed of two parts, one including a device which is mounted on the totalizer and has a finger projecting above it and which is transportable by the totalizer in its jumping action to the other part, which is mount- 125 130

ed on the framework and includes a guide that acts on the finger.

9. In a calculating and recording machine, the combination with a jumping totalizer, and a feeler contained in and arranged to act on register wheels of the totalizer, of feeler-actuating means composed of two parts, one mounted on the totalizer and transportable by it in its jumping action to the other, which is mounted on the framework, and one including an angularly movable device that has a finger, and the other including a guide that acts on the finger at one side thereof.

10. In a calculating and recording machine, the combination with a jumping totalizer, and a feeler contained in and arranged to act on register wheels of the totalizer, of feeler actuating means composed of two parts, one including a device that has a finger and is mounted on the totalizer and the finger of which projects above the totalizer and which is transportable by the totalizer in its jumping action to the other part, which is mounted on the framework and includes a displaceable guide that sometimes acts on the finger to change the direction of its travel and sometimes is forced from its normal position by the finger.

11. In a calculating and recording machine, the combination with a jumping totalizer, and a feeler mounted in and arranged to act on register wheels of the totalizer, of feeler actuating means composed of two parts, one including an angularly movable device which is mounted in and has a finger projecting from the top of the totalizer and which is transportable by the totalizer in its jumping action to the other, which is mounted on the framework and includes a guide that acts on the finger.

12. In a calculating and recording machine, the combination with a jumping totalizer, and a feeler mounted in and arranged to act on register wheels of the totalizer, of feeler actuating means composed of two parts, one including an angularly movable device which has a finger and is mounted in and the finger of which projects from the top of the totalizer and which is movable by the totalizer in its jumping action to the other part, which is mounted on the framework and includes a displaceable guide that sometimes acts on the finger to change the direction of its travel and sometimes is forced from its normal position by the finger.

13. In a calculating machine, the combination with a jumping totalizer and a feeler arranged to act on wheels in the totalizer, of feeler actuating means in which a part mounted on the totalizer and a part mounted on the framework are included, and locking mechanism including a movable device

arranged to be actuated by that part of said means which is mounted on the totalizer, during a jumping action wherein said means has previously actuated the feeler.

14. In a calculating machine, the combination with a carriage, of a device which is mounted thereon and movable relatively thereto and in which a finger is included, and a lever which is mounted on the framework and to which are connected a cam bar and a guide that during a transit of the carriage acts on the finger, which thereafter acts on the cam bar.

15. In a calculating machine, the combination with a traveling totalizer, of a device which is mounted thereon and movable relatively thereto and in which a finger is included, and an angular lever which is mounted on the framework and to one arm of which is affixed a cam bar and to which is connected a guide that during backward movements of the totalizer acts on the finger which thereafter acts on the cam bar.

16. In a calculating machine, the combination with a jumping totalizer, of a device which is mounted thereon and movable relatively thereto and in which a finger is included, and a lever which is mounted on the framework and to which are connected a cam bar and a guide that during jumping movements of the totalizer acts on the finger which thereafter acts on the cam bar.

17. In a calculating machine, the combination with a carriage, of a device which is mounted thereon and movable relatively thereto and in which a finger is included, and a lever which is mounted on the framework and to which are connected a cam bar and a displaceable guide that during some movements of the carriage is displaced by the finger, which during other movements is deflected by the guide and thereafter acts on the cam bar.

18. In a calculating machine, the combination with a traveling totalizer, of a device which is mounted thereon and movable relatively thereto and in which a finger is included, and a lever which is mounted on the framework and to which are connected a cam bar and a displaceable guide that during some backward movements of the totalizer is displaceable by the finger, which during other backward movements of the totalizer is deflected by the guide and thereafter acts on the cam bar.

19. In a calculating machine, the combination with a jumping totalizer, of a device which is mounted thereon and movable relatively thereto and in which a finger is included, and a lever which is mounted on the framework and to which are connected a cam bar and a displaceable guide that during some jumping movements of the totalizer is displaceable by the finger, which during other jumping movements of the

totalizer is deflected by the guide and thereafter acts on the cam bar.

20. In a calculating machine, condition testing and indicating mechanism including 5 a lever to which are connected a cam bar and a finger-deflecting guide.

21. In a calculating machine, condition testing and indicating mechanism including a lever to which is connected a cam bar on 10 which is mounted a finger deflecting guide that is displaceable by the finger.

22. In a calculating machine, condition testing and indicating mechanism including a lever to which is connected a cam bar on 15 which is pivotally mounted a finger deflecting guide that is movable on its pivot from its normal position by the finger.

23. In a calculating machine, the combination with a group of register wheels, a 20 carriage, and a feeler arranged to act on the group of wheels, of feeler actuating means composed of two parts, one mounted on the carriage and including a device that has an upwardly extending arm, and the other 25 mounted on the framework and including a guide that acts on this arm near its upper end.

24. In a calculating machine, the combination with a traveling totalizer, and a 30 feeler arranged to act on register wheels in the totalizer, of feeler actuating means composed of two parts, one mounted on the totalizer and including a device that has an arm projecting above the totalizer, and the other mounted on the framework and including a guide that acts on this arm.

25. In a calculating machine, the combination with a jumping totalizer, and a 40 feeler contained in and arranged to act on register wheels of the totalizer, of feeler actuating means composed of two parts, one including a device that is mounted in and projects above the totalizer, and the other mounted on the framework and including a 45 guide that acts on this arm during a jumping action of the totalizer.

26. In a calculating and recording machine which records computed items in a plurality of zones, the combination with the 50 recording means, of a main carriage, cross footing mechanism including a jumping carriage that makes a reciprocation each time an item is recorded in any zone, a feeler arranged to act on register wheels of the 55 cross footing mechanism, means brought into action automatically as an incident to the recording of items in a predetermined zone, to press the feeler momentarily against the register wheels, and clearance indicating 60 means controlled by mechanism that includes the feeler.

27. In a calculating machine which computes groups of items both separately and 65 all together, the combination of a set of traveling vertical totalizers, a cross footing

totalizer that makes a reciprocation each time an item is registered in a vertical totalizer, a feeler arranged to act on register wheels of the cross totalizer, means brought into action automatically, after items have 70 been registered in a particular vertical totalizer, to press the feeler against the register wheels of the cross totalizer, and clearance indicating means controlled by mechanism that includes the feeler. 75

28. In a calculating and recording machine which records computed items in a plurality of zones, the combination with the recording means, of a main carriage, cross footing mechanism including a jumping carriage that makes a reciprocation each 80 time an item is recorded in any zone, a feeler arranged to act on register wheels of the cross footing mechanism, feeler actuating means held inactive except at periods determined by the main carriage as it travels, mechanism in which an element that is located near the main carriage and another element that acts on and imparts motion to a part of the feeler actuating 85 means are included, an adjustable device mounted on the main carriage and adapted to act momentarily on said first mentioned element just after items are recorded in a calculating zone predetermined by adjustment of this device, and clearance indicating means correlated to the feeler and its actuating means.

29. In a calculating machine, which computes groups of items both separately and 100 all together, the combination of a set of adjustably mounted traveling vertical totalizers, a cross footing totalizer that makes a reciprocation each time an item is registered in a vertical totalizer, a feeler 105 arranged to act on register wheels of the cross totalizer, feeler actuating means held inactive except at periods determined by a specially equipped vertical totalizer as it travels, mechanism in which an element that is 110 located near the path of the vertical totalizers and another element that acts on and imparts motion to a part of the feeler actuating means are included, a device attached to the specially equipped vertical totalizer 115 and adapted to act momentarily on said first mentioned element, just after an item is registered in that vertical totalizer, to press the feeler momentarily against the register wheels of the cross totalizer, and clearance 120 indicating means controlled by mechanism that includes the feeler.

30. In a calculating and recording machine which records computed items in a plurality of zones, the combination with the 125 recording means, of a main carriage that moves step-by-step, cross footing carriage that also moves step-by-step with the main carriage, as an item is recorded in any zone, and then 130

jumps back, a feeler arranged to act on register wheels of the cross footing mechanism, a guide and co-operating devices, the guide automatically moving to working position, at the completion of each entry made in one of the zones, to press said feeler momentarily against said register wheels during the succeeding jump of the cross footing carriage, and clearance indicating means controlled by the feeler and mechanism on which it acts.

31. In a calculating machine, the combination with a totalizer having register wheels, actuating means therefor, and means for effecting a relative reciprocation between said totalizer and its actuating means once for each number entered into a calculation, of clearance proof mechanism including a feeler for said register wheels, a finger connected with said feeler, a spring pressed guide, and means for bringing said spring pressed guide into position to act on said finger to press said feeler momentarily against said register wheels at that particular relative travel of said totalizer and its actuating means wherein the said totalizer should be clear.

32. In a calculating and recording machine which records computed items in a plurality of zones, the combination with the recording means and register wheels, of a

feeler forced to act on said wheels when items are recorded in a predetermined zone, but held inactive when items are recorded in any other zone.

35

33. In a calculating and recording machine which records computed items in a plurality of zones, the combination with the recording means and register wheels, of a feeler forced to act on said wheels when items are recorded in a predetermined zone, but held inactive when items are recorded in any other zone, and clearance indicating means controlled by mechanism that includes the feeler.

45

34. In a calculating and recording machine which records computed items in a plurality of zones and which includes a cross totalizer, the combination with the recording means and register wheels of the cross totalizer, of a feeler forced to act on those wheels when items are recorded in a predetermined zone, but held inactive when items are recorded in any other zone.
